UNITED STATES PATENT OFFICE.

ALBERT BALL, OF CLAREMONT, NEW HAMPSHIRE, ASSIGNOR TO THE SULLIVAN MACHINE COMPANY, OF SAME PLACE.

GANG-DRILL ROCK-CHANNELING MACHINE.

SPECIFICATION forming part of Letters Patent No. 392,398, dated November 6, 1888.

Application filed May 10, 1887. Serial No. 237,730. (No model.)

To all whom it may concern:

Be it known that I, ALBERT BALL, a citizen of the United States, residing at Claremont, in the county of Sullivan and State of New Hampshire, have invented certain new and useful Improvements in Gang-Drill Rock-Channeling Machines; and I do hereby declare the following to be a full, clear, and exact description of the invention, which will enable others skilled in the art to which it appertains to make and use the same.

My invention relates to that class of rock-channeling drills where the machine requires to be constantly fed along a track forward for a distance and then back at a slow and preferably uniform speed, while at the same time an engine works a gang of steel drills and rapidly strikes them against the rock, thereby cutting a channel; and my improvements herein to be described have for their object a simple and effective method of causing these feed movements, and also of stopping and reversing by hand the movement of the machine on the track, and also, without interfering with these changes by hand, automatic stopping and reversal of the movement along the track when the desired terminal points are reached, and a simple and practical way of doing this, and, incidentally, an economical way of taking up the thrust wear of the boxes to the feed-reversing shaft.

In the accompanying drawings, which show so much of my channeling-machines as is necessary for the understanding of my device herein sought to be patented, like letters in different drawings refer to the same parts.

Figure 1 is a top view of one of my gang-drill-car frames mounted on its wheels and track and with the feed-engine and devices for governing the feed of the car along the track. Fig. 2 is a longitudinal sectional view through the line α α , Fig. 1, showing in elevation the feed devices. Fig. 3 is an enlarged view, as shown in Fig. 2, of the driving-worm and the devices for taking up the wear in the boxes caused by the thrust of the same endwise. Fig. 4 is an end view of Fig. 3. Figs. 5 and 6 are enlarged views, the one sectional, as shown in Fig. 2, and the other an end view 50 of the shipper-lever with its rocker-shaft, &c.

The drill-car A is mounted on axles B and car-wheels C c c' c', which move on the track D D'. The two wheels c' c' on the front track, D, I make double-flanged, so as to insure a close guidance of the car, and so preventing any variation which is liable in other machines, as they are now built, with single-flanged wheels to bind the gang of drills in the cut. The rail on which the double-flanged wheels move is planed true and straight. A gear, E, is made as a projecting flange to one of the wheels, C, and into this gear works the gear F at the end of a shaft, G, which is driven by the worm-gear H, Fig. 2. This gear F is so arranged that it can be slid back on its shaft G so as to be out of gear with the gear E when it is desired to move the machine freely without affecting the feed mechanism.

The driving-worm I, Fig. 2, is near the end of the feed driving-shaft K. This shaft K extends across the full length of the machine, and is provided with squared ends k, so that the shaft can be turned by a crank by hand. This is a great convenience when it is desired to move the machine a short distance without the use of steam—e. g., in shifting gangs of drills.

The machines are exposed to much dirt and sharp wearing grit. I have devised a method of having the feed worm-gears I and H run in a tight metal case or box, 7, which is kept partly full of oil and makes a very satisfactory protection and oiler.

The power is obtained from a feed-engine, L, Fig. 1. This turns a bevel-gear, M, which interlocks with a pair of bevel-gears, N N', facing opposite ways. They are intended to be always in gear and revolve in opposite ways. They are both placed on the shaft K, on which they move freely, except as one or the other may be clutched. As a part of each of these gears N N' is a collar with clutch O O'. The corresponding two sliding clutches, P P', are splined or keyed on the shaft K, with free longitudinal movement, each having as a part of it a collar with a grooved recess, Q Q', which receives a shipper-fork, R R'. These shipper-forks are secured to the shipper-bar S.

As shown in the drawings, the clutch P is in gear with O, and the bevel N is turning too

the shaft K and its worm I, as shown by the arrow, and the worm-gearing the shaft G and its gear F, as shown by the arrow. This turns the gear E and the car-wheels forward 5 in a direction from the clutch that is out of gear, O' P', toward the clutch that is in gear, O P. To stop the feed it is only necessary to throw the clutch that is in gear out of gear without moving the shipper-shaft far enough 10 to throw the other in gear. The car will thereupon immediately stop. As soon as the reverse movement of the shipper-shaft is continued the clutch O' P' will be in gear and the car will be forced in the opposite direction. 15 My devices contemplate moving this shipper-shaft either by hand or having the car itself cause the movement by the interposition of a fixed obstacle on the track at the points where the reversal of feed is desired, 20 and I will now proceed to describe my methods of doing this.

T is a lever, which is splined to a rocker-shaft, 2. This rocker-shaft has two secure bearings, and upon it (and with it) as a fulcrum the lever moves when hand-power is used. The link 3 and catch 4 fasten the lever-arm to the shipper-shaft. To work the latter by hand it is only necessary to move the lever T forward or back sufficiently. For 25 the automatic action of the lever I use obstructions U U', which are secured to the track in line of the rod V, having projecting ends v v'. This rod passes freely through a hole, w, Fig. 5, in the rocker W, and has a washer 30 on it (Nos. 5 and 6, Fig. 2) at each side of the rocker. Between this washer and suitable obstructions on the rod V, (Z Z'), I place spindle-springs Y Y', set in cases or frames a little shorter than the spring. These cases, as shown 35 in the drawings, are the obstructions Z Z'. One of the clutches, P Q, being in gear, the spiral springs are not under tension, the car not having reached an obstruction. As soon as the obstruction U is reached by the end v 40 the rod V will be forced back and will compress the spring Y toward the rocker W until the end of the case Z reaches the washer 6, when the rocker will be carried with the rod V, the shaft 2 turned correspondingly, and 45 the lever and shipper-bar thrown forward, carrying the clutch P out of gear with Q. As soon as the clutch is out of gear the spring Y, 50 that is under tension, is strong enough to carry the shipper-shaft along farther until the clutch P' is in contact with O', whereupon the car is moved in the opposite direction.

It is obvious that the springs could be relied on without the cases Z Z'; but I prefer to use what is absolutely positive, and so avoid 55 straining the spring. So, also, the springs could be left off and a stoppage caused without the subsequent automatic reversal.

It is obvious that as the driving-worm I has alternately to drive the car down and back 60 on its track there will be considerable thrusting wear on the box-bearings of the worm-shaft, and I have devised a simple and effect-

ive method of taking up this wear by the use of interchangeable boxes h h', (see Fig. 3,) between the shoulders of which the respective 70 ends of the worm-flanges rest. These boxes, together with the worm and shaft, are set in the heavy metal cover of the case 7, (also used, as aforesaid, for an oil-holder,) the ends of which are threaded. Working in these threads 75 are the hollow nuts g g', with notched heads g' g', for each of which there is a spring nut-lock, f, which holds the screw firmly in its place. These screws do not touch the shaft, but have a thrust-bearing on the little boxes h h, and as fast as the latter are worn the heads and screws 80 g g' are turned up. When worn out, the boxes h h are replaced by new ones in a few minutes, and the bearings are the same as at first.

It is obvious that instead of a single shaft 85 V, with a single shipper-lever and rocker-shaft and attachments, the shaft V can be divided and two shipper-levers and attachments provided, one for each end of the machine, and to produce each a movement of the shipper-shaft one way. Similarly, instead of a single 90 driving-gear M driving the two gears N and N', there could be a separate driving-gear for each of the latter, effecting a similar result; also, instead of two single-faced clutches P P', 95 a single double-faced clutch to work between the two gears N and N' could be used with a single shipper-fork.

In channelling with a gang-drill, if the feed be not stopped the instant the end of the cut 100 is reached, serious strain on the drills results. The advantage of an automatic reversal of the feed in addition to the economy of labor is therefore manifest.

Having thus described my invention, what 105 I claim, and desire to secure by Letters Patent, is as follows:

1. In a gang-drill rock-channeling machine, the combination, in the machine-car carrying the propelling-engine, of the gears N N', rotating oppositely, the laterally-movable alternative clutches P P', and the rods V and S, with connections with said clutches, substantially as and for the purposes described.

2. In a gang-drill rock-channeling machine, 115 mechanism for moving the same on a track, consisting of a driving-gear, M, a pair of gears, N N', driven in opposite directions and each attached to a clutch, O O', and a worm-shaft, K, with the two clutches P P', and its worm I, 120 and the gear H, shaft G, and gears F and E, substantially as described.

3. In a gang-drill rock-channeling machine, 125 and in combination with suitable driving mechanism for feeding the same, the two alternative clutches P P' and a shipper-rod, S, operated by a hand-lever, T, and link 3, attached to the catch 4, said hand-lever being rigidly connected to the rod 2, provided with the lug W, having suitable connection with the rod V, by 130 means of which the device can be made automatic, substantially as described, and for the purposes set forth.

4. In a gang-drill rock-channeling machine,

in combination with suitable driving mechanism for feeding said machine, the alternative clutches P P' and shipper-shaft S, the shifting lever T, link 3, and rocker-shaft 2, substantially as and for the purpose set forth.

5. In combination with a gang-drill rock-channeling machine and suitable mechanism for feeding the same upon its track, the obstructions U U', the rod V, the rocker-shaft 2 W, the lever T, the shipper-shaft S, and the clutches P P', substantially as and for the purpose set forth.

6. In combination with a gang-drill rock-channeling machine and suitable mechanism for feeding the same upon its track, the obstructions U U', the rod V, springs Y Y', the rocker-shaft 2 W, the lever T, the shipper-shaft S, and the clutches P P', substantially as and for the purposes set forth.

20 7. In the mechanism for feeding a gang-drill rock-channeling machine upon its track, a feed driving-shaft, K, provided with longitudinal adjustable bearings h h', in combination with adjusting-screws g g' and screw-sets 25 f, substantially as and for the purpose set forth.

8. The combination, with the machine-car carrying the operating-engine and provided with the alternating clutches O P and O' P', and rods v v', connected therewith, of the tracks D D', upon which said car is adapted to 30 run, and arms U U', removably connected to one of said tracks, for the purposes set forth, substantially as described.

9. In a gang-drill rock-channeling machine, in combination with suitable driving-power 35 and devices for applying and reversing the same, a feed driving-shaft carrying the worm I, a worm-gear, H, with shaft G, and a gear, F, arranged to be movable forward and back on its shaft G, so as to be thrown in or out of 40 gear with the truck-wheel gear E, substantially as and for the purpose described.

In testimony whereof I affix my signature in presence of two witnesses.

ALBERT BALL.
